UNITED STATES PATENT OFFICE.

ERNEST L. BULLOCK AND ELMER S. UMSTEAD, OF PROVIDENCE, RHODE ISLAND.

SOLDERING-IRON FURNACE.

Application filed April 27, 1925. Serial No. 26,076.

To all whom it may concern:

Be it known that we, ERNEST L. BULLOCK and ELMER S. UMSTEAD, both citizens of the United States, residing at Providence, in 5 the county of Providence and State of Rhode Island, have invented new and useful Improvements in a Soldering-Iron Furnace, of which the following is a specification.

10 This invention relates to certain new and useful improvements in a soldering iron furnace especially of the vapor or gaseous fuel type, and it has for an object to provide a structure wherein the gas flame is downwardly directed into the combustion chamber and the products of combustion are carried off through the bottom thereof, toward the front.

15 The invention further resides in the provision of a loose, fluted floor tile of fire brick forming the bottom of the combustion chamber, the flutes or grooves providing sub-surface outlet passages for conducting the products of combustion to the flue which latter extends beneath the furnace and up at the back thereof.

20 A further and equally important object is to incorporate or enclose the gas and air pipes in the walls of the furnace for pre-heating both the gas and air before commingling.

25 Further, the invention resides in the provision of insulation and dead-air spaces about the furnace and the flue, and also in an improved burner structure.

30 Other objects and salient features of construction will be described and set forth as the description progresses, reference being made to the accompanying drawings where-40 in:

Figure 1 is a front elevation of the improved furnace.

Figure 2 is a side elevation thereof;

45 Figure 3 is a vertical sectional view thereof on line 3—3 of Figure 1, with the coiled piping omitted:

Figure 4 is a bottom plan view of the burner nozzle and

50 Figure 5 is a bottom plan view of the loose fire brick.

Referring more in detail to the accompanying drawings, the body 1 of the soldering iron furnace is preferably of cast iron lined on its interior with fire brick 2 and 55 covered exteriorly with a heavy or thick layer 3 of asbestos or like heat-insulation.

The insulating covering 3 includes a dead-air space 4 extending about the combustion chamber at its top, sides and back.

The fire brick lining 2 defines a combustion chamber 5 which has a recessed bottom, in the recess 6 of which is loosely mounted a fire brick 7. The bottom face 8 of this brick is fluted, grooved, or otherwise provided with channels 9 through which the products of combustion pass and make their escape to the flue.

Directly above the loose fire brick 7 is a downwardly directed Venturi burner 10 disposed in the roof of the combustion and soldering iron chamber 5 so as to send its flame jet down toward said fire brick. The fuel for the burner nozzle is conveyed through two pipes, one an air pipe 11 and the other a gas pipe 12, both embedded in flat coil form in the opposite side walls of the furnace, as depicted in Figure 1. The particular fluid is delivered to the lower end of the respective coil from a valve-controlled supply pipe 13, the upper ends of the coils extending inwardly over the combustion chamber and thence upwardly to a preliminary mixing chamber 14 spaced above the furnace. The combined fluid fuel thence passes to the valve chamber 15 from which it discharges through the jet orifice 16, across the air chamber 17, and into the orifice 18. A valve 19 is designed to coact with the orifice 16 for causing the fluid fuel to escape in jet form across the intervening chamber or space 17 at which point an additional supply of air, at atmospheric pressure, is commingled with the fuel to effect proper combustion. The additional supply of air is admitted through the lateral port 20 of a nipple 21, the size of the port 20 being controlled by a ring like valve or nut 22 threaded on the nipple for movement across said port. This construction and arrangement involves the principle of the Bunsen burner or Venturi tube. The gaseous fuel thence passes downwardly to the nozzle 10 in which is inserted an orifice or grooved plug for discharging the gas to produce an efficient flame. The products of combustion thence pass downwardly and through the passageways beneath the loose fire brick toward the front of the chamber and into the front leg 23 of the flue.

It will be noted that this leg is forward of the front door 24 of the furnace and is protected by the insulating covering of the

same which forms a forwardly extending platform 25 between the front door 24 and a rest 26 for the soldering irons. The flue leg 23 opens downwardly into one end of a horizontal, connecting flue 27 which extends beneath the furnace and connects at its opposite end to the main flue 28, the insulating covering inclosing both the horizontal flue 27 and the lower portion of the main flue.

In use, the soldering irons are placed in the chamber 5 on the fire brick or floor, in which position the flame from the burner impinges thereon, and the waste products of combustion pass beneath the fire brick into the flue. The coils 11 and 12, being embedded in the furnace walls become highly heated to further the formation of the combustible fuel. The fire brick being loose permits easy removal thereof for cleaning and renewal.

Having thus described our invention, what we claim as new and desire to secure by Letters Patent is:—

23. 1. A soldering iron furnace comprising a chamber lined with fire brick and having a recessed bottom, and a loose fire brick in the bottom recess defining therewith an outlet passage to a flue.
30. 2. A soldering iron furnace comprising a chamber having a recessed bottom, a fire brick loosely disposed in the bottom recess and formed in its underside with grooves defining outlet passages, a flue to which the passages connect, and a burner directed downwardly toward the fire brick.
40. 3. A soldering iron furnace comprising a chamber having a recessed bottom, a fire brick loosely disposed in the bottom recess and formed in its underside with grooves defining outlet passages, a flue to which the passages connect, said fire brick adapted to support soldering irons, and a burner directed downwardly toward the fire brick.
45. 4. A soldering iron furnace comprising a chamber lined with fire brick and formed in its bottom with a recess, a removable fire brick loosely arranged in the recess and defining with the wall thereof an outlet passage, a flue connected to the outlet passage, a burner arranged in the top of the chamber, and a heat-insulating covering for the cham-

ber provided with a dead-air space over the top and about the sides thereof.

5. A soldering iron furnace comprising a chamber opened at one end, a tool support outwardly of the chamber opening, a flue opening beneath said opening of the chamber, a burner in the chamber, and a fire brick loosely disposed within the chamber having a passage leading to the flue opening.

6. A soldering iron furnace comprising a chamber having a bottom flue passage, air and gas pipes embedded in opposite sides of the chamber, a mixing chamber with which the two pipes connect and a burner nozzle connected with the mixing chamber and directed downwardly toward the bottom flue passage.

7. A soldering iron furnace comprising a chamber, a burner in its upper portion, a flat coil-air pipe and a flat-coil gas pipe embedded in the opposite sides of the chamber, a superposed mixing chamber with which the two pipes connect, and a connection between the mixing chamber and the burner.

8. A soldering iron furnace comprising a chamber, a burner in its upper portion, upwardly extending fuel and air pipes embedded in the opposite side walls of the chamber, a superposed mixing chamber connected to the upper ends of the pipes and to the burner, an auxiliary mixing chamber interposed between the first mixing chamber and the burner, and an auxiliary air supply for the second mixing chamber.

9. A soldering iron furnace comprising a chamber, a burner in its upper portion, upwardly extending fuel and air pipes embedded in the opposite side walls of the chamber, a superposed mixing chamber connected to the upper ends of the pipes and to the burner, an auxiliary mixing chamber interposed between the first mixing chamber and the burner, an air conduit for the auxiliary chamber having a lateral port opening to the atmosphere, and a ring-like valve threaded on the conduit for movement over the port thereof.

In testimony whereof we have signed our names to this specification.

ERNEST L. BULLOCK.
ELMER S. UMSTEAD.
